ABRADING, POLISHING, OR LIKE SURFACING TOOL

Filed March 21, 1932

BY *J. Stanley Bush*
ATTORNEY.

UNITED STATES PATENT OFFICE

ALPHONSE FISET, OF CAMBRIDGE, MASSACHUSETTS

ABRADING, POLISHING, OR LIKE SURFACING TOOL

Application filed March 21, 1932. Serial No. 600,330.

This invention relates to abrading, polishing or like surfacing tools, and has more particular reference to an improved device for holding sheets of abrasive, polishing or like material so that the same may be conveniently and effectively employed in abrading, polishing or otherwise finishing surfaces.

An object of the invention is to provide a holder of the above kind which is extremely simple and durable in construction and efficient in use.

Another object of the invention is to provide a holder of the above kind which may be conveniently manipulated, by which the sheet of finishing material may be securely held in proper condition for use, and which will permit the ready application or removal of the sheet of polishing material for renewal from time to time as found necessary.

Other objects and features of the invention will become apparent from the following description when considered in connection with the accompanying drawing, in which:

Figure 1 is a perspective view of a tool embodying the present invention.

Figure 2 is a side elevational view thereof.

Figure 3 is a transverse section on line 3—3 of Figure 2; and

Figure 4 is a perspective view of the body of the tool with the sheet clamping and hand grip forming members removed.

Referring more in detail to the drawing, the tool shown may be conveniently made of stamped metal and consists of a body member 5 formed from a single sheet of metal centrally folded upon itself and having its free end portions directed laterally in opposite directions to form co-planar wings 6. Disposed against and covering the under surfaces of the wings 6 is a base plate 7 having its margin tightly folded over and upon the marginal edge portions of the wings 6 to securely fasten the base plate 7 to the latter and to form a support for the sheet of abrading, polishing or like material 8.

The fold of the sheet from which the body 5 is formed has the intermediate portion thereof cut away as at 9, and the end portions

of the fold which are left are given a tubular formation to form hinge barrels 10.

Oppositely facing substantially S-shaped clamping and hand grip forming members 11 are hinged to and arranged at opposite sides of the body 5, the upper edges of said members 11 being formed with interfitting hinge barrels 12 to receive a hinge pin 13 which also passes through the hinge barrels 10. It will be seen that the upper outwardly curved portions of the members 11 cooperate to form a rounded hand grip, while the lower outwardly directed portions of said members 11 are arranged to overlie the wings 6 when the members 11 are swung downwardly to the full line operative position of Figures 1 to 3, inclusive. Thus, when the sheet of abrading, polishing or like material 8 is arranged against the under side of the plate 7 and has its side edge portions folded over upon the wings 6, the lower portions of the members 11 will tightly grip said folded over edges of the sheet 8 with a force proportional to the tightness with which the members 11 are gripped at their upper portions. In other words, when the upper portions of the members 11 are gripped tightly, said members are forced to swing downwardly and inwardly toward each other with their lower portions engaging the folded over edge portions of the sheet 8 and securely clamping the latter in place between the wings 6 and said lower portions of the members 11.

The hinge pin 13 has frictional engagement in the barrels 12 of the members 11, and one end of the pin 13 projects beyond the adjacent end of the body 5 and is formed with a finger loop or handle 14. Thus, by swinging the loop or handle 14 in one direction, one of the members 11 may be swung outwardly and upwardly to release the adjacent edge portion of the sheet 8, while the other edge portion of the sheet 8 may be released by swinging the handle or loop 14 in the opposite direction. This arrangement facilitates the ready application of a sheet 8 to the tool proper. For instance, assuming that a new sheet is being applied, and that one of the members 11 has been raised as indicated by dotted lines in Figure 1, an edge of the

sheet may be folded upon the wing 6 at the side of the tool where the raised member 11 is located. The handle or loop 14 may then be swung in a direction to lower this member 11 which has been initially raised so as to bring it into gripping engagement with the folded over edge of the sheet 8, and to simultaneously swing the other member 11 outwardly and upwardly. The folded over edge 10 portion of the sheet 8 is thus gripped, and the opposite member 11 is raised so that the other edge portion of the sheet 8 may be folded conveniently to be subsequently held by manual movement of the second member 11 15 downwardly and inwardly to operative position. The frictional engagement of pin 13 permits slippage thereof relative to the hinge barrels 12 so that either member 11 may be moved to raised or released position while 20 the other member 11 remains stationary, said other member 11 being prevented from movement by its engagement with the base of the tool or the adjacent folded over edge of the sheet 8. However, when both members 11 25 are brought into gripping engagement with the folded over edges of the sheet 8, they may be gripped and moved relatively toward each other and relative to the pin 13 to tightly hold the sheet 8 in place while the tool is in use. Obviously, a tool of this kind is used by 30 simply grasping the hand grip portion and rubbing the surface to be abraded, polished or otherwise finished with the under surface of the sheet 8.

35 While I have shown and described what I believe at present to be the preferred embodiment of my invention, it is nevertheless to be understood that various changes may be made in the details and manner of constructing the tool without departing from the spirit and scope of the invention as claimed.

40 What I claim as new is:

45 1. A tool of the character described comprising a flat base having a central upstanding body of rib-like form and adapted to have the opposite edge portions of a sheet of abrading, polishing or like material folded over and upon opposite side portions thereof, 50 and oppositely facing substantially S-shaped members hinged to the upper edge of said rib-like body, said hinged members having upper portions cooperating to form a hand grip and lower portions arranged to clamp the 55 folded over edge portions of the sheet upon the opposite side portions of the base when said members are gripped.

60 2. A tool of the character described comprising a flat base having a rigid upstanding body in the form of a rib, a hinge pin parallel with and journaled in the upper edge of said body, and combined hand grip forming and sheet clamping members arranged at opposite sides of the body and provided with 65 hinge barrels at their upper edges frictionally

receiving said hinge pin, said hinge pin having a projecting end formed to provide a handle for manipulating said members.

3. A tool of the character described comprising a body formed from a sheet of metal bent upon itself and having its ends directed laterally to form oppositely extending wings, a base plate secured to and covering the under surfaces of said wings, the fold of said body forming sheet being centrally cut away and having the remaining end portions thereof shaped to form hinge barrels, substantially S-shaped sheet clamping and hand grip forming members having hinge barrels on their upper edges, and a hinge pin journaled in the hinge barrels of the body and frictionally engaging in the hinge barrels of said members.

4. A tool of the character described comprising a body formed from a sheet of metal bent upon itself and having its ends directed laterally to form oppositely extending wings, a base plate secured to and covering the under surfaces of said wings, the fold of said body forming sheet being centrally cut away and having the remaining end portions thereof shaped to form hinge barrels, substantially S-shaped sheet clamping and hand grip forming members having hinge barrels on their upper edges, and a hinge pin journaled in the hinge barrels of the body and frictionally engaging in the hinge barrels of said members, said hinge pin projecting at one end of the body and formed to provide a handle.

5. A tool of the character described comprising a base having a central longitudinal body in the form of an upstanding rib, and relatively movable sheet clamping members arranged at opposite sides of the body and hinged to the upper edge of the latter, said sheet clamping members having outwardly directed upper portions cooperating to form a hand grip by means of which said members are swung downwardly and inwardly into gripping engagement with the folded over edge portions of a sheet applied to the under surface of the base.

In testimony hereof I affix my signature.

ALPHONSE FISSET.
